UNITED STATES PATENT OFFICE.

CLINTON W. DICKINSON, OF LA CROSSE, WISCONSIN.

BEARING FOR DISK FURROW-OPENERS.

1,217,423.

Specification of Letters Patent. Patented Feb. 27, 1917.

Original application filed February 19, 1909, Serial No. 478,957. Divided and this application filed June 9, 1915. Serial No. 33,005.

To all whom it may concern:

Be it known that I, CLINTON W. DICKINSON, a resident of La Crosse, in the county of La Crosse and State of Wisconsin, have 5 invented certain new and useful Improvements in Bearings for Disk Furrow-Openers, of which the following is a full, clear, and exact description.

The invention relates to bearings for disk furrow-openers.

10 The subject-matter of this application is a division of the invention set forth in an application filed by me February 19, 1909, Serial No. 478,957 for disk furrow openers.

15 In seeding-machines, it is now common practice to employ furrow-openers consisting essentially of a pair of oppositely disposed disks mounted in angular relation to one another for opening a furrow, these being generally known as "double disk" furrow-openers. In this class of devices, each disk is independently journaled in the support, and a desideratum is to provide a bearing structure which is as narrow as possible 20 to leave the greatest possible clearance between the furrow-openers which are usually employed in gangs in a seeding-machine.

The invention also designs to provide an improved manner whereby the disk-spindle 25 or trunnion may be inserted into the bearing in the support. In accordance with this object of the invention, the spindle is insertible into the bearing from that side at which the disk is disposed and held in the 30 bearing by means fixed to the support on the same side thereof, the disk being connected to the spindle after the latter has been inserted in the bearing. Resultantly, the disks may be conveniently removed for 35 sharpening without removing the bearing-spindles rotating therewith, and means for securing the spindle in its bearing may be formed to serve as a closure for confining the lubricant in the bearing and need not be 40 removed when the disk is removed.

45 The invention is designed to provide an improved simple construction of bearing for the spindle of a disk-furrow opener.

The invention consists in the several novel 50 features hereinafter set forth and more particularly defined by claims at the conclusion hereof.

In the drawings: Figure 1 is a side elevation of a furrow-opener embodying the 55 invention. Fig. 2 is a horizontal section

through the axes of the disk spindles, the disk-spindles or bearing-blocks being shown in elevation. Fig. 3 is a central, vertical, longitudinal section of the boot between the disks. Fig. 4 is a perspective of one of the 60 disk-spindles or bearing-blocks. Fig. 5 is a perspective of the cup-shaped dust-guard. Fig. 6 is a perspective of one of the plates for holding the disk-spindles or bearing-blocks in its bearing.

65 The furrow-opener is usually connected to the frame of a seeding-machine by a drag-bar 11 to which is secured a support or boot 12 in which is formed a seed-conduit 13 through which the seed is conducted into 70 the furrow formed by the opener. A disk 14 is disposed at each side of the boot and these disks are journaled at an angle to each other relatively to open a furrow, the disks being mounted so their lower portions will 75 be in contact or close proximity, thence diverging toward the rear to widen the furrow as they are drawn through the soil.

80 Each disk is revolvably connected to the boot or support 12, the latter being formed with an annular wall 15 which serves as a bearing for the disk-spindle. A spindle or bearing-block 16 is provided for each disk and is journaled in the bearing 15 of the support, the spindles being journaled at an 85 angle to one another, corresponding to the angular relation of the disks and are oppositely mounted in said bearing, and the periphery 17 of each spindle 16 fits into the recess or opening in the bearing 15 and the inner face 19 of each spindle is conoidal to form a thrust-surface having a rolling contact with the other spindle, whereby the lateral thrust of one spindle will be received 90 and opposed by the other. Each spindle is 95 formed with a reduced portion 20 which extends through a plate 22 having an opening 23 therein which fits around said reduced portion and which confines the spindle against outward movement in its bearing, 100 by engaging the shoulders 17' at the inner end of the reduced portion 20 of the spindle. Each plate 22 is secured to one of the sides 105 of the support by screws 24. The outer end of each spindle is provided with a reduced terminal 25 which is square in form, or other suitable shape, to extend through a correspondingly shaped opening in the disk, so that the disk and spindle will rotate together. A washer 26 engages the outer face 110

2
of each disk and is secured to clamp the disk on the spindle by a screw 27. A cup-shaped dirt-guard 28, usually formed of sheet metal, is clamped between the disk and the shoulder 29 of the spindle, and comprises an inturned flange 30 which extends around the periphery of plate 22 and prevents the entry of dirt between the disk and the plate 22 and to the bearing for the spindle.

10 In practice, the soil presses against the lower portions of the outer faces of the disks so that inward thrust or pressure will be exerted on the disk-spindles, so that the latter will receive lateral thrust from each other at the contacting line or point below the spindle axes. It also occurs in practice that the seeding-machine is at times driven backwardly so that the lower portions of the disks will be pressed outwardly and to keep these spindles properly positioned in the bearing and prevent them from becoming cramped therein, a wall or abutment 30' is formed on the support and fits between the supported portions of the revolving spindles. Under these abnormal conditions the abutment receives lateral thrust at a point opposite the contacting point of the spindles. Thus the spindles will be at all times 30 truly held in the bearings in such manner that excessive friction will be avoided.

An oil-duct 31 is formed in the support and communicates at its lower end with the opening or chamber in which the spindles 35 rotate, so that lubrication may be supplied to the inclosed spindles, and the walls of the bearing in which they are journaled. By employing a plate 22 which is secured to the support and through which the reduced 40 spindle portion 20 extends, the side-opening in the bearing is reduced to form a well in which the lubricant will be retained by the plate.

In assembling the device, the spindles are 45 first placed into the bearing 15 from the opposite sides thereof and the plates 22 are then respectively secured to the outer sides of the bearing. The spindles will then be held in the bearing against lateral movement in either direction. The cup-shaped guards 28 and disks 14 will then be placed on the reduced terminal 25 of the spindles respectively and securely clamped between washers 26 and shoulders by screws 27. 50 When it is desired to remove one of the disks for sharpening, or to replace one, it is only necessary to remove the screw 27 when the disk will be free to be withdrawn laterally from the reduced terminal of a spindle. 60 Thus, each disk may be removed without disturbing the spindles or bearing-blocks.

As a result of mounting the spindles rotatably in the bearing and securing them against outward movement by means at the 65 outer sides of the bearing, and connecting

the disk to the spindle after the latter is held in the bearing, by means, the disks may be removed for sharpening or replacement without removing the spindles. The improved cup-shaped dirt-guard effectively prevents the entry of dirt to the bearing and prevents it from being clogged. The closure plate extending around a reduced portion of the spindle prevents the escape of lubricant from the bearing. The construction throughout is one which makes it possible to employ narrow elements while affording the necessary bearing-surfaces to keep the disks in rotating and proper relation.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A journal bearing including, in combination, a supporting bracket having a forwardly and downwardly disposed surface surrounding an axially arranged recess formed in said surface, a bearing block having a circular base member rotatably received by said recess, and a circular reduced portion projecting laterally and axially from said base member, a bearing plate secured to the side of said bracket and engaging with the outer face of said base-member in a manner to retain said bearing block in rotative relation with said bracket, said plate having a central opening that receives the reduced portion of said bearing block, said reduced portion terminating in a short angular portion, a rotatable element provided with an axial angular opening adapted to receive the angular portion of said bearing-block, and means for securing said rotatable element to said bearing block.

2. A journal bearing including in combination a support, and bracket having a forwardly and downwardly disposed surface surrounding an axially arranged recess formed in said surface, a bearing-block having a circular base-member rotatably received by said recess and a circular reduced portion projecting laterally and axially from said base-member, a bearing-plate secured to the side of said bracket and engaging with the outer face of said base-member in a manner to retain said bearing block in rotative relation with said bracket, said plate having a central opening that receives the reduced portion of said bearing block, said reduced portion terminating in a short angular portion, a rotatable element secured on said angular portion of the bearing block, means for securing said rotatable element to said bearing-block, and a washer mounted upon the reduced portion of the bearing.

block in a manner to rotate therewith and disposed between said plate and the rotatable element.

3. A journal bearing including in combination a support and bracket having a forwardly and downwardly disposed surface surrounding an axially arranged recess formed in said surface, a bearing-block having a circular base-member rotatably received by said recess and a circular reduced portion projecting laterally and axially from said base-member, a bearing-plate secured to the side of said bracket and engaging with the outer face of said base-member in a manner to retain said bearing-block in

rotative relation with said bracket, said plate having a central opening that receives the reduced portion of said bearing-block, said reduced portion terminating in a short angular portion, a rotatable element secured 20 on said angular portion of the bearing-block, means for securing said rotatable element to said bearing-block and a dust cap held on the block and disposed between said plate and the rotatable element and having 25 an inturned flange around said plate.

CLINTON W. DICKINSON.
